(57) **CLAIM**

The ornamental design for a rounded play yard, as shown and described.

DESCRIPTION

FIG. 1 is a perspective view of a rounded play yard. FIG. 2 is a right side view of the play yard of FIG. 1. FIG. 3 is a left side view of the play yard of FIG. 1. FIG. 4 is a front view of the play yard of FIG. 1. FIG. 5 is a rear view of the play yard of FIG. 1; and, FIG. 6 is a top view of the play yard of FIG. 1. There is no fabric covering the exposed legs shown in any of FIGS. 1–6. The features shown in broken lines are for illustrative purposes only and do not form part of the claimed design.
